PROGRAMMABLE KEYBOARD

BACKGROUND OF THE INVENTION

The present invention relates to input devices for data processing systems and particularly to a programmable keyboard for such purpose.

A programmable keyboard is a device for feeding control instructions and/or data into a data processing device, such as an electronic computer, which can determine the inscription and thus the significance of each individual key. Such a keyboard offers very flexible input possibilities and can have a reduced number of keys, compared with keyboards whose keys have fixed meanings, so that higher typing speeds result.

Such a programmable keyboard—the designation "key" is here to be understood in the broad sense to relate to a finger-operated signalling means—is known in the form of a character-writing electron beam tube in whose screen there are inserted small wires which function as "keys" to produce a signal when contacted by a finger which acts to detune an electric bridge. The tube is able to write characters onto the screen in the vicinity of such a wire, which characters indicate the significance of the respective wire-key.

While such keyboards function satisfactorily, the single tube is relatively large and expensive to produce. Even a minor malfunction might necessitate replacement of the tube. Moreover, the actuated area of the tube is not readily distinguishable from the areas adjacent thereto.

SUMMARY OF THE INVENTION

It is a primary object of the present invention to overcome or minimize these drawbacks and difficulties.

Another object of the invention is to improve the construction of programmable keyboards.

The present invention provides a programmable keyboard which has a small depth, which can be economically fabricated, and which may be so designed that an actuated key is depressed and clearly distinct from the non-depressed keys and can also be locked in this position if desired, and in which individual malfunctioning keys can be easily replaced.

A programmable keyboard in which the meaning of the individual keys is determined by a data processing device is characterized, according to the present invention, in that each of the individual keys is in the form of a cathode-ray tube.

According to one embodiment of the invention, each cathode-ray screen tube can be depressed, by finger pressure, in a direction perpendicular to the screen surface. In this case it is desirable to connect each cathode-ray screen tube to a mechanical member which actuates a switch when the tube is depressed.

In another embodiment of the invention, the screen surface, or another screen viewing surface, of each cathode-ray screen tube is provided with an electrically conductive, particularly a transparent, coating which triggers a signal when the surface is contacted.

In further accordance with the present invention, character-producing beam deflection voltages are fed to all cathode-ray screen tubes in parallel while the intensity modulation voltages for the beams are individually fed to the tubes. Moreover, staircase voltages are fed to the cathode-ray screen tubes to produce rows and/or columns of characters.

BRIEF DESCRIPTION OF THE DRAWINGS

FIG. 1 is partly a schematic elevation view of a portion of a programmable keyboard according to the present invention.

FIG. 2 is a plan view of the keyboard of FIG. 1.

FIG. 3 is a schematic illustration of one embodiment of a circuit arrangement used with the keyboard of the invention.

FIG. 4 shows the upper part of a cathode-ray tube with a transparent, conductive coating and serving as a key, there also being shown a finger of an operator, and circuits connected to the coating.

DESCRIPTION OF THE PREFERRED EMBODIMENTS

FIG. 1 shows a portion of a keyboard in approximately its actual size. The keyboard is composed of a plurality of small cathode-ray tubes 1 each having an associated tube socket 2 supported by a U-shaped bar 3. Each bar 3 rests on a compression spring 4 which can be compressed by a few millimeters and which is fastened to the center of the bar, the other end of the spring resting on, and being immovable with respect to, a stationary U-shaped bar 5. The stationary bar 5 carries, between its upper ends, a microswitch 6 disposed inside bar 3 and arranged to be actuated by means of a key peg 6a extending therefrom. Each tube socket 2 bears a plug 2a for actuating the associated key peg 6a and electrical connections 2b.

The front plate 1a of each tube 1, which is just above the tube screen, extends slightly above a cover plate 7, the tubes being guided in circular cutouts 7a in the cover plate 7. Each tube 1 can be pressed downward a few millimeters against the force of spring 4 by slight finger pressure on its front plate 1a, the associated plug 2a then also pressing the key peg 6a disposed therebelow downward so that the associated microswitch 6 is actuated.

In FIG. 3 there are shown the portions of tubes 1 which contain deflection plates 1x, 1y in one row and in another row those portions containing the tube beam intensity modulation grids 1h, not all the tubes of a keyboard being represented. The microswitches 6, which are actuated by depressing the associated tube, are also shown schematically in a row, again less than all of the microswitches being shown.

By closing a microswitch 6 a voltage is applied to one input line of coding matrix 8 which generates a preferably digital code identifying the closed microswitch 6. This code is conducted through a parallel-series converter 9 and into a line 10 and through this line 10 to an electronic computer.

The computer determines which meaning a signal produced by each depressed key is to have and controls the inscribing of characters on the tube screens of a desired number of keys so that the meaning of each such key is indicated to the operator by the characters appearing on the screen of the associated tube 1, whereupon the operator can depress the key whose tube screen presents the appropriate indication.

As is known an image repeat memory is required for the simultaneous visual indication of a plurality of characters on the screen of a cathode-ray tube, which memory emits the data required for writing all of the characters on the screen in a cyclic, repetitive manner to provide a flickerfree representation of the characters. The image repeat memory may be a part of the computer memory, but often it is advisable to use a separate memory 11, which receives information representing data from the computer through a line 12 and an electronic coupling system 13. Memory 11 may be, for example, a feedback coupled delay line memory which cyclically and repetitively emits the data for writing all of the characters for the tubes.

In order to write each character, memory 11 indicates, by delivering a code to character generator 14, which character is to be written. The character generator 14 then emits a sequence of x and y deflection voltages to the deflection amplifiers Vx and Vy which effect the "stylus-type" writing of the character, character generator 14 also generally activating an intensity modulation control for writing the individual characters, which control is effected by an intensity modulation control circuit 15.

The characters to be written must furthermore be positioned on the screen. When only one line of characters is to be written, this can be accomplished by a staircase voltage fed to horizontal deflection amplifier Vx to produce a stepwise horizontal shift after each character has been written. In the circuit of FIG. 3 a staircase voltage generator 16 is provided for this purpose, this generator being cyclically and repetitively controlled by the signals from the image repeat memory 11.

In the operation of the circuit of FIG. 3, the output voltage of the x deflection amplifier V_x are fed in parallel to the x deflection plates $1x$ of all of tubes 1 and the output voltage of the y deflection amplifier V_y are fed in parallel to the deflection plates $1y$ of all of the tubes. This means that character writing beam movements corresponding to the respective total contents of the image repeat memory 11 take place simultaneously in all tubes 1. The intensity modulation control grids $1h$ of tubes 1, however, are individually connected to the intensity control circuit 15 and the intensity control circuit 15 also receives signals from the image repeat memory 11 which determine on which tube 1 a character whose code is just being emitted from memory 11 is to appear. The other tubes are then blanked by the intensity modulation circuit 15.

It is quite clear that the characters could be written in a column, i.e. vertically, on the screens of tubes 1 if the staircase voltage generator 16 were connected to y deflection amplifier V_y and, moreover, that a number of rows can be written on the screen when a staircase voltage generator is connected to each of amplifiers V_x and V_y , both generators being controlled by image repeat memory 11. In order to write two horizontal rows, for example, the staircase voltage generator connected to amplifier V_y would need have only two voltage steps which are selectively produced at the proper time under the control of image repeat memory 11.

The key designations which can be represented on the screen of tubes 1 are not limited to alphanumeric characters.

As is known, it is also possible to produce certain different types of graphic representations on a screen when suitable digitally controlled beam control generators, such as vector generators in particular, are used. Such representations may thus appear as programmed key designations on all or some of the keys in the form of symbols, e.g. switching symbols or track diagram symbols.

Thus the computer, when it executes or is to begin a program needing the cooperation of a human operator, can inscribe significances in the form of characters, signs, or graphic representations on a desired number of the tube-keys by feeding corresponding data to the repeat memory, and the operator can initiate an operation according to the meaning of a tube-key by depressing it.

FIG. 4 shows the upper part of a cathode-ray tube serving as a key which can be actuated, instead of depressing the tube, by merely touching its upper face with a finger. The head-part of the glass bulb 1 of the tube, including the front plate 1a, is coated with a thin layer 17 of a transparent, conductive material such as zinc-oxide. A metal ring 18, which surrounds and contacts the layer 17 on its cylindrical part, is connected via wire 19 to an electrode of a glow-lamp 20. The other electrode of the glow-lamp 20 is connected, via a resistance 21, to the secondary winding 22 of a transformer 23-22. The other end of winding 22 is connected to earth. The primary winding 23 of the transformer 23-22 is connected to an a-c power supply. The glow-lamp 20 is, together with a phototransistor 24, encased in a light-tight casing 25.

When a finger 26 of the operator touches the layer 17 on the upper surface 1a of the tube, an a-c circuit is established from earth via the resistance (as symbolized by 27) of the operators body, the layer 17, ring 18, wire 19, glow-lamp 20, resistance 21, winding 22, to earth. The glow-lamp 20 fires and illuminates the phototransistor 24 causing it to emit a signal to terminal 28, which is connected to one input line of coding matrix 8. When finger 26 is taken away from the surface 1a, the said a-c circuit is interrupted, glow-lamp 20 extinguishes, and the signal of phototransistor 24 ceases. Of course, another photoelectric device could be used instead of phototransistor 24.

It will be understood that the above description of the present invention is susceptible to various modifications, changes and adaptations, and the same are intended to be comprehended within the meaning and range of equivalents of the appended claims.

I claim:

1. In a data processing system including a programmable keyboard composed of a plurality of individual key elements for writing information into the data processing system, which system includes means for storing a representation of the information to which each key element is to relate, the improvement wherein each said element comprises an individual cathode-ray tube having a visible image producing screen and the system includes an electrical connection connected between said storing means and said elements to receive signals corresponding to said representations for causing an indication of the information to which said representations relate to appear on selected ones of said screens, said electrical connection comprising: an image memory connected for receiving, under control of the system, selected ones of said representations to produce image data corresponding to the indication to appear on at least one said screen; circuit means connected between said memory and said tubes for producing on said screen the indication determined by said image data produced for the respective tube; and a plurality of switch means connected in the processing system and each operatively associated with a respective one of said tubes to be actuated by an operator's finger contact on said tube for providing to the system an identification of the tube with which said switch means is associated; whereby actuation of each said switch means initiates delivery into the system of data corresponding to the identification of its associated tube.
2. An arrangement as defined in claim 1 wherein each said tube is mounted to be displaced by finger pressure in a direction perpendicular to the surface of its display screen.
3. An arrangement as defined in claim 2 further comprising a plurality of actuation members each mounted on a respective one of said tubes, and wherein said switch means comprise a plurality of switches each arranged to be actuated by the actuation member of a respective tube when said tube is displaced.
4. An arrangement as defined in claim 1 wherein each said tube includes an electrically conductive coating disposed on a screen surface and connected to said switch means and a power source connected to the coating, said switch means being arranged to initiate an electrical signal when said coating is contacted by an operator's finger which connects said coating to ground.
5. An arrangement as defined in claim 4 wherein said coating is transparent.
6. An arrangement as defined in claim 1 wherein said circuit means comprise beam deflection voltage means connected in parallel to all of said tubes and beam intensity control means having a plurality of individual controlled outputs each connected to a respective tube.
7. An arrangement as defined in claim 6 wherein said circuit means further comprise means connected to said tubes for cylindrically producing a voltage having a staircase waveform to control the tube beam deflection so as to permit each tube to produce characters at different points on its screen.
8. An arrangement as defined in claim 4 wherein said switch means comprise, for each said tube, a glow-lamp, said conductive coating is connected to an electrode of said glow-lamp, the other electrode of said glow-lamp being connected to earth via a resistance and the secondary winding of a transformer, and said switch means for each said tube further comprises a photoelectric device arranged to be illuminated by said glow-lamp as long as an a-c circuit firing said glow-lamp is established by touching said conductive coating.
9. An arrangement as defined in claim 7 wherein said memory is an image repetition memory which cyclically and repetitively emits the image data associated with the indication to appear on said at least one tube screen, and said circuit means further comprise a character generator connected between said memory and said deflection voltage means.
10. An arrangement as defined in claim 1 further comprising coding means connected between said switch means and the data processing system for producing an individual signal identifiable by the system upon the actuation of each respective switch means.
